UNITED STATES PATENT OFFICE

2,527,038

MEAT TENDERING MACHINE

Hendrik Stukart, La Porte, Ind., assignor to U. S.
Slicing Machine Company Inc., a corporation
of Indiana

Application December 3, 1945, Serial No. 632,324

3 Claims. (Cl. 17—25)

1

This invention relates, in general, to meat tendering machines of the general type disclosed in my Patent 2,339,890, issued January 25, 1944, but relates more specifically to an improved feeding mechanism for the material to be operated on, and which is particularly adapted, though not necessarily limited in use, in connection with such a machine.

One of the objects of the present invention is to provide an improved feeding mechanism which is adapted to feed the material, such as meat or the like, to the tenderizing elements.

Another object of the invention is to provide an improved conveyor mechanism, and improved operating means therefor, whereby intermittent steps of advancing movement may be imparted thereto.

A further object is to provide improved means for embodying a back stop mechanism for the conveyor, to prevent retrograde movement.

A still further object is to provide improved mechanism of this character, which will be simple, durable and cheap in construction, and effective and efficient in operation.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings exemplifying this invention, in which

Figure 1 is a top plan view of a machine of this character, constructed in accordance with the principles of this invention, parts thereof being broken away for the sake of clearness.

Figure 2 is a longitudinal sectional view taken on line 2—2, Figure 1.

Figure 3 is a vertical sectional view taken on line 3—3, Figure 2, with parts omitted.

Figure 4 is a detail sectional view taken on line 4—4, Figure 1, on an enlarged scale.

Figure 5 is a detail sectional view taken on line 5—5, Figure 4.

Figure 6 is an enlarged sectional view taken on line 6—6, Figure 1.

The particular exemplification of the tendering machine here illustrated, embodies a crosshead 10, carried by an arm 11, of an eccentric strap 12, which latter co-operates with an eccentric member 13, connected with a pulley 14, attached to a shaft 15, so that when the pulley and eccentric are rotated, the crosshead 10 will be reciprocated in a generally vertical direction, and will be given an orbital movement.

2

The pulley 14 is rotated by means of an endless belt 16, which passes thereover and also over a pulley 17, connected to a shaft 18, of a motor 19. All of the above-referred-to parts are mounted within a frame or casing 20, which constitutes the body portion of the machine.

The ends of the crosshead are provided with supporting shafts or studs 21, journaled at the ends of oppositely disposed links 22, the other ends of the links being rigidly fixed to a transverse shaft 23, supported in bearings 24, suitably mounted. A tine supporting member 25 is detachably secured to the crosshead 10, in any suitable manner, and carries a plurality of longitudinally spaced apart pairs of tines 26.

The construction of the above referred to parts forms no part of the present invention, except in so far as these parts may enter into the general combination. The said construction, however, is substantially the same as that disclosed in United States Patent 2,408,747 issued October 8, 1946.

The construction, operation and location of the parts so far described, is for the purpose of operating the tools or tines to tender a piece of meat, or other substance, which is placed on a supporting base 27, and the operation of the machine is such that the tines 26 move in an orbit, passing through slots 28, provided in the support 27, to pierce the piece of meat, or other substance. This operation of the tines not only pierces and tenderizes the meat, but also causes the meat to be advanced or fed to the left in Figure 2 of the drawings.

35 A cap plate 29, having spaced grooves 30 for the reception of the ends of the tines, is removably supported by or connected to the frame or housing of the machine, in any suitable manner, such as by means of pivotally mounted bolts 31, 40 that pass through openings 32 in the cap member 29, and nuts 33 threaded thereon.

In order to convey the meat or material to the support 27, to be operated upon by the tines 26, there is provided a conveyor mechanism, embodying laterally spaced endless elements 34, preferably formed of coiled material, such as coiled springs, any number of which may be provided. These elements are preferably arranged in an inclined position, and pass over a roller 35, disposed adjacent the support 27, and also pass over another roller 36, the roller 36 being preferably mounted at a higher elevation than the roller 35, so that the endless elements will travel in a downwardly inclined plane. Each of the rollers 35 and 36 may, if desired, be provided with grooves

37, in which the endless elements run. The endless elements are preferably disposed within a trough-like construction 38, and one of the runs of the elements passes over and rests upon a support 39, to prevent sagging of the elements under the weight of their load.

Arranged at one end of the roller 35 is a clutch device, of any desired or suitable construction, but which preferably embodies a clutch member 40, a portion 41 of which telescopes into the end of the roller 35, and such telescoping portion is provided with peripheral recesses 42, in which recesses balls 43 are arranged. These balls are urged in one direction by means of spring 44, the recesses being so shaped that when the element 40 is moved in one direction with respect to the roller 35 (counter-clockwise in Fig. 4), a binding action will occur between the roller 35 and the element 40, to move the roller 35 in one direction. When, however, the element 40 is moved in the opposite direction, the element 40 will be released so as to move independently with respect to the roller 35. A spring 45, preferably a coil spring, encompasses the end of the roller 35, and acts upon the element 40, tending normally to move the latter in a direction to release or render the clutch inactive. To accomplish this action, one end of the spring 45 is anchored to a fixed pin on a side of the device, and the opposite end 46 engages and acts upon an arm 47, connected to the element 40. The end 48 of the arm is engaged, and actuated against the stress of the spring 45, by another arm 49, that is secured to the shaft 23.

As the crosshead 10 is reciprocated through the movements of the eccentric strap 12 and the member 11, the shaft 23 will be rocked through the medium of the links 22, and as the arm 49 is also rocked through the medium of the shaft 23, the arm 47 will impart an oscillatory movement to the clutch member 40, and thereby impart an intermittent step of advancing movement to the endless conveyor elements 34.

A back stop clutch mechanism is provided for the conveyor, and is preferably located at the other end of the roller 35. This back stop clutch is of a construction similar to the clutch mechanism for advancing the conveyor, but is designed to operate in the opposite direction from the direction of operation of the clutch advancing mechanism. This back stop clutch preferably embodies a member 50, which is maintained stationary, and has a portion telescoping into the end of the roller. This telescoping portion is provided with peripheral recesses 51, in which spring-controlled balls 52 are mounted. The recesses are so constructed that when the roller 35 is relatively moved in one direction with respect to the member 50, there will be a binding action therebetween, and the roller 35 will be maintained against retrograde movement, but when the roller is moved in the opposite or advancing direction by the portion 41 of the clutch member 40, the feeding roller 35 will be free to advance the conveyor elements 34.

It will therefore be seen that the back stop mechanism will permit the conveyor elements to be advanced upon each operation of the arm 46.

A delivery chute or slide 53 may be provided to receive the material from the support 27, for directing it out of the machine, and may be supported by a bracket or member 54. If desired,

walls 55 may be arranged at the sides of the conveyor, to form a trough or chute in which the material advances. By the use of coiled resilient elements 34 for the conveyor members, the tension of such elements will maintain them taut.

While the preferred form of the invention has been herein shown and described, it is to be understood that various changes may be made in the details of construction and in the combination and arrangement of the various parts, within the scope of the claims, without departing from the spirit of this invention.

What is claimed as new is:

1. A machine of the character described, for tendering substance such as meat, embodying a reciprocating member, substance piercing means carried by said member, means to operate said member to move said piercing means through a predetermined orbital path to pierce and move the substance through the machine, means to advance the substance to said piercing means, means to operate the said advancing means and embodying a clutch device, and means connected with said reciprocating member and co-operating with said clutch device for controlling the operation thereof.

2. A machine of the character described, for tendering substance such as meat, embodying a reciprocating member, substance piercing means carried by said member, means to operate said member to move said piercing means through a predetermined orbital path to pierce and move the substance through the machine, means to advance the substance to said piercing means, means to operate the said advancing means and embodying a clutch device, said clutch device embodying an arm forming a part thereof, a rock shaft, means operatively connecting said rock shaft with said reciprocating member to be operated by the latter, and means connected with said rock shaft for engagement with said arm to actuate the latter.

3. A machine of the character described, for tendering substance such as meat, embodying a reciprocating member, substance piercing means carried by said member, means to operate said member to move said piercing means through a predetermined orbital path to pierce and move the substance through the machine, means to advance the substance to said piercing means, means to operate the said advancing means and embodying a clutch device, said clutch device embodying an arm forming a part thereof, a rock shaft, means operatively connecting said rock shaft with said reciprocating member to be operated by the latter, means connected with said rock shaft for engagement with said arm to actuate the latter, and back stop mechanism for the said advancing means.

HENDRIK STUKART.
